Rudolph J. Lutz

Attorney

UNITED STATES PATENT OFFICE.

FRANK MADLE, OF BERWYN, ILLINOIS, ASSIGNOR TO CRUVER MANUFACTURING COMPANY, OF CHICAGO, ILLINOIS, A CORPORATION OF ILLINOIS.

RECEPTACLE.

Application filed February 23, 1924. Serial No. 695,659.

This invention relates to improvements in receptacles and more particularly to that type of receptacle comprising a metal body covered with celluloid, the invention having, 5 as one of its main objects, to provide a metallic receptacle having a mouth portion of an area equal to or slightly greater than the interior thereof and stiffening or reinforcing the rim of said mouth portion to prevent distortion of the same, and providing 10 a smooth, rounded edge or surface therefor by means also utilized for securing the celluloid covering for the annular wall of the receptacle so firmly to the latter as to prevent removal thereof, and to thereby also 15 adapt said mouth to be sealed or closed by a cover fitted into instead of over the same.

Another object of the invention is to provide means for easily and securely engaging 20 a cover element with the rim of the mouth of the receptacle without rendering said cover element difficult of removal by digital engagement thereof, and utilizing said means to effect a far more efficient engagement between the celluloid covering for the annular 25 wall of the receptacle and the rim of the mouth of the latter than could otherwise be obtained.

Another object of the invention is to provide 30 a cover for the receptacle consisting principally of a mirror and wherein the exposed surface of the latter is of an area almost equal to that of the open mouth of the receptacle and wherein the area of the celluloid casing for the cover projects only slightly beyond the rim of the mouth of the receptacle when the latter is mounted thereon.

The preferred embodiment of the invention 40 is illustrated in the accompanying drawings, wherein:

Fig. 1 is a perspective view of the receptacle and Fig. 2 is a similar view of the cover therefor.

Fig. 3 is a fragmentary diametric section 45 of the receptacle and its cover.

Fig. 4 is a fragmentary perspective section of the metallic receptacle devoid of the celluloid covering.

Fig. 5 is a similar view of the celluloid 50 covered receptacle.

Fig. 6 is a similar section of the metallic element of the cover.

Fig. 7 is a similar section of the completed 55 cover.

The metallic receptacle is in the instance illustrated, formed from a single piece of metal and includes the bottom wall A, the cylindrical wall B and the double-thick annular flange C formed at substantially the 60 juncture of said bottom A and wall B. The latter terminates in an outwardly overturned annular flange D extending substantially parallel with said wall B, thereby providing an annular groove opposing the 65 flange C. A strip E of celluloid of a length equal to the outer circumference of the wall B and of a width equal to the distance between the bottom of the groove formed by the flange D and the opposed face of the 70 flange C, is disposed between the latter and said bottom of said groove, the flange D being contracted upon the edge-portion of said strip to secure the same. Thereafter said flange D, and the opposed portion of the 75 wall B, are indented or offset to provide a plurality of inwardly extending projections F at the mouth of the receptacle, such indentations serving, obviously, to more firmly engage the edge-portion of the strip E 80 against removal.

A covering disk G, of celluloid, having an annular flange H of an inner diameter substantially equal to the extreme diameter of the flange C, is mounted to cover the bottom wall A and receive the flange D, the free edge of the flange H being then turned in, under the influence of heat, to cover the flange C and abut against the other edge portion of the strip E to thereby hold the 90 latter securely in place.

The cover for the receptacle consists of a metal ring J which is substantially cylindrical and very shallow. This is provided 95 on one edge with an annular inwardly extending flange K and an opposite edge with the annular outwardly extending flange L which terminates in an annular lip M opposing and converged toward the ring J. The flange K extends, preferably, at a 100 slightly acute angle to the ring J and constitutes a support for the edge portion of a mirror N which is framed by the ring J and is of such thickness that, when resting on the free edge of said flange K, its opposite or silvered face is flush with the outer surface of the flange L.

The celluloid casing or jacket O for the cover comprises a circular disk which lies 105 upon the mirror N and the outer surface of 110

the flange L and is provided with an annular flange P the free edge portion of which is turned to embrace the free edge of the lip M of flange L, said lip being thus completely covered externally and the channel or annular recess between it and the ring J is adapted to receive the rim of the mouth of the receptacle.

The ring J is preferably of slightly less diameter adjacent the flange K than adjacent the flange L so that, in mounting the same on the rim of the receptacle, it may be sprung over the projections F and be thus very firmly held in place. The extreme outer diameter of the ring J is slightly less than the inner diameter of the rim of the mouth of the receptacle and when forced into place almost hermetically seals the latter.

The construction described is very advantageous in that the mouth of the receptacle is wholly unobstructed except by the very small, almost imperceptible projections F. Said rim is rendered very stiff and difficult of distortion by the overturned flange C and the celluloid strip E engaged therewith.

The ring J, while of very small dimensions in radial cross-sections is rendered very stiff by the flanges K and L thereof and by its engagement with the flange of the celluloid disk O. It preferably also closely hugs the annular edge of the mirror N, the diameter of which is only slightly less than that of the mouth of the receptacle and nearly all of whose area is exposed to view.

The receptacle is intended to constitute a vanity case to contain face powder and a powder puff and it is particularly desirable, in a device of this character to provide as large a mirror as possible proportionate to the dimensions of the receptacle.

The above-described structure, while providing the several advantages set forth, presents an unusually neat appearance and is easily and cheaply manufactured.

Obviously, said structure is capable of some modification within the definition of the appended claims without departing from the invention which is illustrated in its preferred embodiment only.

I claim as my invention:

1. A receptacle including a body portion and a removable cover therefor, said body portion bordered at its open end by an outwardly extending peripheral flange, said cover comprising a continuous ring-like element including a portion adapted to be received within the flanged mouth of the receptacle, said portion provided at one end with an inwardly extending peripheral flange, a disk of a relatively inflexible material supported upon said flange and having its edge embraced by said portion, an outwardly extending peripheral flange at the other end of the latter overlapping the

flange of the body structure, and a disk of celluloid having an overturned peripheral edge portion receiving said last-named flange and maintaining said disk in place.

2. The combination with a receptacle including a peripheral wall provided along one edge with a continuous outwardly overturned flange to thereby provide a continuous peripheral groove opposing the other edge of said wall, a strip of celluloid engaged along one edge in said groove and clamped between said flange and said wall, an outwardly projecting flange along the other edge of said wall, and a disk of celluloid having an overturned peripheral flange engaged with said last-mentioned flange of said wall and with the other edge-portion of the strip, of a removable cover for said receptacle comprising a ring-like element conforming in contour with the receptacle wall and having a peripheral wall portion adapted to be received within the mouth of the receptacle, said peripheral wall portion of said cover having an inwardly and an outwardly extending flange respectively, at its opposite ends, and a peripherally flanged disk engaged with said outwardly extending flange.

3. The combination with a receptacle including a metallic peripheral wall provided along one edge with a continuous outwardly overturned flange to thereby provide a continuous peripheral groove opposing the other edge of said wall, a strip of celluloid engaged along one side edge in said groove and clamped between said flange and said wall, an outwardly projecting flange along the other edge of said wall, and a disk of celluloid having an overturned peripheral flange engaged with said last-named flange of said wall, said first-named flanged edge of said wall provided with a plurality of inwardly offset portions, of a removable cover for said receptacle comprising a ring-like element conforming in contour with the receptacle wall and having a peripheral wall portion adapted to be received within the mouth of the receptacle and frictionally engage said offset portions for holding said cover in place, said peripheral wall portion of said cover having an inwardly and an outwardly extending flange, respectively, at its opposite ends, and a peripherally flanged disk engaged with said outwardly extending flange.

4. The combination with a receptacle including a metal body open at one end, said open end bordered by an outwardly overturned peripheral flange having its free portion spaced from the peripheral wall of the receptacle to thereby provide an annular groove opposing the bottom end of said receptacle, an annular flange at said last-named end, a covering strip for said peripheral wall engaged along one edge in said

groove and clamped between said flange and the opposed portion of said wall, a covering disk for the lower end of said receptacle, and a peripheral flange on said disk for covering the bottom annular flange of the receptacle and abutting against the other edge of said strip, of a removable cover for the receptacle comprising a ring-like element conforming in contour with the receptacle wall and having a peripheral wall portion adapted to be received within the mouth of the receptacle, said peripheral wall portion of said cover having an inwardly and an outwardly extending flange respectively, at its opposite ends, and a peripherally flanged disk engaged with said outwardly extending flange.

5. A receptacle cover comprising a con-

tinuous ring-like element including a vertically disposed annular portion adapted to extend into the mouth of the receptacle and oppose the inner face thereof, said portion provided at one end with an inwardly extending peripheral flange, a disk of a relatively inflexible material supported upon said flange and having its edge embraced by said portion, an outwardly extending peripheral flange at the other end of the latter, and a disk of celluloid having an overturned peripheral edge portion receiving said last-named flange and maintaining said disk in place.

In testimony whereof, I have hereunto set my hand, this 14th day of January, A. D. 1924.

FRANK MADLE.
